CLAIM

The ornamental design for a perfume bottle, as shown.

DESCRIPTION

FIG. 1 is a perspective view of a perfume bottle showing my new design;

FIG. 2 is a side view of the perfume bottle shown resting on its bottom surface while the viewer is directly opposite a corner of the cap of the container;

FIG. 3 is another side view of the perfume bottle resting on its bottom with the bottle rotated 60° about its vertical axis from the position shown in FIG. 2;

FIG. 4 is a view looking down on the top of the cap; and

FIG. 5 is a bottom plan view.

FIG. 1
